UNITED STATES PATENT OFFICE

153,686

DESIGN FOR A CLOTHING DISPLAY RACK

Geraldine Hinkle, San Francisco, Calif.

Application June 30, 1947, Serial No. 140,016

Term of patent 14 years

(Cl. D30—9)

To all whom it may concern:

Be it known that I, Geraldine Hinkle, a citizen of the United States, residing at San Francisco, in the county of San Francisco and State of California, have invented a new, original, and ornamental Design for Clothing Display Rack, of which the following is a specification, reference being had to the accompanying drawing, forming part thereof.

I claim:
The ornamental design for a clothing display rack, as shown.

GERALDINE HINKLE.
